RIDING BOOT

Jack Alesci, Fort Sam Houston, Tex.

Application October 8, 1936, Serial No. 104,733

6 Claims. (Cl. 36—45)

This invention relates to riding boots, and more particularly to a means in combination with a conventional pair of riding boots to assist in the bending or breaking of the leg portion thereof with respect to the shoe portion thereof.

An object of this invention is to provide a means insertible interiorly of a pair of conventional riding boots which will effect a proper bending or breaking between the leg and shoe portions of the boot.

Another object of this invention is to provide a lining which is adapted to be removably positioned interiorly of a boot which is so constructed that it will readily maintain its position within the boot while at the same time assisting in the proper bending or breaking of the leg portion of the boot with respect to the shoe portion thereof.

A further object of this invention is to provide in a lining of this character means for anchoring the lining within the boot to prevent the lining from creeping upwardly or turning within the boot.

With the foregoing and other objects in view, the invention will be more fully described hereinafter, and will be more particularly pointed out in the claims appended hereto.

In the drawings, wherein like symbols refer to like or corresponding parts throughout the several views,

Figure 1 is a longitudinal section, partly broken away and in section, of a riding boot having a device constructed according to an embodiment of this invention mounted therein.

Figure 2 is a view similar to Fig. 1 but showing the boot with the upper portion thereof bent forwardly with respect to the shoe portion thereof.

Figure 3 is a longitudinal section of the lining.

Figure 4 is a detail front elevation of the lining spread out in flat form.

Referring to the drawings, the numeral 10 designates generally the shoe or lower portion of a riding boot, and the numeral 11 designates the leg or upper portion of the boot. In riding boots at present available after the boot has been in use for a period of time the break between the front of the leg portion 11 and the upper portion of the shoe 10 becomes enlarged to the point where substantially all of the stiffness in the leg portion 11 has been taken out so that the boot loses its original shapeliness and will not stay in position on the leg of the wearer, the upper or leg portion 11 gradually sliding or moving downwardly.

It is in order to eliminate this objectionable

feature of riding boots that a lining, generally designated as 12, is inserted within the boot. The lining 12 comprises an upper or leg stiffening member 14 which is constructed of relatively stiff leather or like material, and is formed in a sheet 5 which is so cut that it will readily wrap around the leg of the wearer with the open vertical edges thereof disposed at the rear of the leg. The upper edge 13 of the leg portion 14 has a configuration such that when the lining 12 is in applied 10 position this upper edge 13 will be substantially flush with the upper edge 15 of the outer leg portion 11. The leg member 14 is provided at the lower edge thereof with an upwardly offset portion or recess 16 which is adapted to engage 15 around the front, or slightly above the instep, of the boot, and at each end of the recess 16 there is provided a downwardly extending portion or lobe 17 which, when the lining 12 is in applied 20 position, are adapted to be disposed slightly above the ankle of the wearer.

The lower edge of the stiffening member 14 terminates in upwardly offset portions or recesses 18 which are adapted to be disposed at the rear of the boot slightly above the heel portion of the 25 shoe 10. A quarter lining is provided, this quarter lining being designated generally at 19.

The quarter lining 19 comprises a pair of side or wing members 20 which are adapted to engage on opposite sides of the heel of the wearer, and 30 the wing or side members 20 are connected together adjacent their upper edges by means of a connecting strip 21 which is preferably integral with the side members 20. This connecting strip 21 is upwardly offset from the upper edges of the 35 side members 20 and is adapted to engage at its upper edge with the recessed portion 16 of the upper member 14. The upper edges of the side members 20 and the connecting strip 21 underlap the stiffening member 14 at the lower edge 40 thereof and are secured thereto by means of stitching 22 or the like.

The confronting edges of the side or wing members 20 are disposed in spaced apart relation, and a forwardly extending instep member 23 has the 45 rear edge thereof secured as by stitching 24 to the confronting or forward edges of the side or wing members 20. This instep member 23 is adapted, when in applied position, to engage over the instep of the wearer and along the sides of the foot, 50 terminating at its forward end adjacent the toe portion of the shoe 10. The lower edges of the side members 20 and the instep member 23 are so formed that they will substantially engage the upper surface of the insole of the shoe 10 adjacent 55

the marginal edges thereof so that no portion of the side members 20 and the instep member 23 will engage beneath the foot of the wearer.

The quarter lining 19 is preferably constructed of leather which has a greater degree of pliability than the stiffening member 14, so that the quarter lining can readily conform to the configuration of the shoe and foot and can readily bend therewith.

10. In use the lining 12 is preferably inserted into the boot before the boot has been placed on the foot and leg. The quarter lining 19 is positioned within the interior of the shoe 10, and as shown in Figs. 1 and 2 this quarter lining 19 terminates 15 at its upper edge slightly above the break or bend 25 at the front of the boot and slightly above the break or bend 26 at the rear of the boot, so that the foot portion 10 can readily move relative to the leg portion 11 thereof. The free edges of the 20 stiffening member 14, and the free edges of the side or wing members 20 are disposed at the rear of the boot and substantially contact with each other so that there will not be a ridge or groove 25 at the rear of the boot which might cause discomfort or irritation to the wearer. When the leg of the wearer is bent or inclined forwardly with respect to the foot, the stiffening member 14 will prevent bending of the leg portion 11 of the boot at any point above the break or bend 25. 30 This condition will obtain throughout the life or use of the boot. Where the leg of the wearer is bent or inclined rearwardly, as shown in Fig. 1, the stiffening member 14 will prevent bending of the upper leg portion 11 except at the break or bend 26.

35 The quarter lining 19 will prevent the stiffening member 14 from riding or moving upwardly on the leg of the wearer, and as the upper edges of this quarter lining 19 extend slightly above the breaks or bends 25 and 26 there will not be any tendency for the stiffening member 14 to break or bend at the lower edge thereof.

40 A boot having a lining constructed according to this invention mounted therein will retain its shapeliness throughout the life thereof and will, therefore, present a better appearance than a boot not having such a lining. This lining 12 will also serve as a guard to protect the leg of the wearer. The protection is similar to that afforded by the leg 11 of the boot and in addition thereto.

45 When the foot is in the boot it will engage the instep lining 23 and the quarter lining 19 which will tend to hold all of the various linings in place and against creeping upwards.

50 It is obvious that various changes and modifications may be made in the details of construction and design of the above specifically described embodiment of this invention without departing from the spirit thereof, such changes and modifications being restricted only by the scope of the following claims.

55 What is claimed is:

1. In a riding boot having a shoe and a leg portion, a stiff lining removably mounted in the leg 60 portion with its edges adjacent one another at the rear part of the leg portion, the lower edge of the lining having front and rear upwardly-offset portions, a quarter lining of flexible material fitted down into the quarter of the shoe portion and

having front and rear projecting parts on its upper edge mating with the upwardly-offset portions of the leg lining and secured thereto, said quarter lining having a front extension having therein an inverted V-shaped opening slit 5 through the lower edge thereof, and an instep member secured to the sides of the opening and extending forwardly into the instep portion of the shoe.

2. A boot having a flexible ankle portion, and 10 means for definitely positioning at different heights the wrinkles occurring in said portion when the same is flexed so that said wrinkles around the angle portion will be disconnected from each other. 15

3. A boot including, a foot portion and an upper portion, said upper portion having its lower end secured to said foot portion, means for reinforcing the upper portion of said upper above the ankle while leaving the ankle portion unreinforced to make said upper portion substantially rigid, whereby the lower end of said upper around the ankle of the boot remains flexible, and means on the lower end of the reinforcing means for definitely allocating the breaks at different 25 heights in the flexible portion of the upper around the ankle portion when said upper is flexed with relation to the foot portion.

4. A boot including, a foot portion and an upper portion, said upper portion having its lower 30 end secured to said foot portion, a reinforcing means within the upper portion rendering the upper portion of the upper substantially rigid, and said reinforcing means terminating above the foot portion with lobes extending downwardly of the 35 sides of the boot with recesses extending upwardly above the front and rear portions of the foot portion whereby creasing of the unreinforced upper portion will be permitted at different heights around the flexible portion of the upper adjacent 40 to the foot portion.

5. A boot in accordance with claim 4 wherein the recesses between the lobes of the reinforcing means extend to different heights at the front and rear. 45

6. A boot including, a foot portion and an upper portion, said upper portion having its lower end secured to said foot portion, said foot portion having substantially rigid front and rear upwardly extending projections with lower side portions, 50 a reinforcing means within the upper portion rendering the upper portion of the upper substantially rigid, and said reinforcing means terminating above the foot portion with lobes extending downwardly of the sides of the boot with recesses 55 extending upwardly above the front and rear portions of the foot portion, said lobes extending toward the lower side portions of the foot portion and the upwardly extending portions of the foot portion extending toward the recesses in the lower 60 portion of the reinforcing means, whereby creasing of the unreinforced upper portion will be permitted at different heights around the flexible portion of the upper adjacent to the foot portion, the creases being limited at the front and rear by 65 the lobes of the reinforcing and at the sides below said lobes by the upward projections of the foot portion.

JACK ALESCI.
